Demian K. Jackson(57) **CLAIM**

The ornamental design for bike trailer connector, as shown and described.

DESCRIPTION

FIG. 1 is a perspective view of a bike trailer connector showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof; and,

FIG. 8 illustrates the design used in a bike trailer.

Those portions of the illustrated design indicated by broken line form no part of the claimed design.
